United States Patent Office

Des. 196,286
Patented Sept. 10, 1963

196,286

HEATER

Jesse Raymond Johnson, Taylor Hollow Road,
Gowanda, N.Y.

Filed Nov. 16, 1962, Ser. No. 72,516

Term of patent 14 years

(Cl. D81—10)

FIG.1

FIG.2

FIG.3

FIG.4

FIG.5

FIG.6

FIG. 1 is a perspective view of a heater showing my new design;

FIG. 2 is a front elevation;

FIG. 3 is a side elevation;

FIG. 4 is a top plan view of the same;

FIG. 5 is a side elevation opposite to FIG. 3; and

FIG. 6 is a back elevation.

The screen which is fragmentarily shown in FIGS. 1 and 2 for ease of illustration is understood to cover the entire panel area shown.

I claim:

The ornamental design for a heater, as shown and described.
